US0D1099051S

(12) **United States Design Patent** (10) **Patent No.:** **US D1,099,051 S**
(45) **Date of Patent:** **** Oct. 21, 2025**

(54) **HAND CONTROLLER**

(71) Applicant: **Fliteboard Pty Ltd.**, Byron Bay (AU)

(72) Inventor: **Marc Newson**, Byron Bay (AU)

(73) Assignee: **FLITEBOARD PTY LTD**, New South Wales (AU)

(**) Term: **15 Years**

(21) Appl. No.: **29/932,925**

(22) Filed: **Mar. 15, 2024**

(30) **Foreign Application Priority Data**

Sep. 15, 2023 (AU) 202316206

CLAIM

The ornamental design for a hand controller, as shown and described.

DESCRIPTION

FIG. 1 is a rear, upper left side perspective view of a hand controller according to our new design;

FIG. 2 is a rear view thereof;

FIG. 3 is a front view thereof;

FIG. 4 is a top view thereof;

FIG. 5 is a bottom view thereof;

FIG. 6 is a right side view thereof;

FIG. 7 is a left side view thereof;

FIG. 8 is a front, lower left side perspective view thereof;

FIG. 9 is a front, lower right side perspective view thereof;

FIG. 10 is a front, upper left side perspective view thereof; and,

FIG. 11 is a front, upper right side perspective view thereof.

1 Claim, 11 Drawing Sheets
